TROPHY CUP OR THE LIKE

Jean Mayeur, Forest Hills, N.Y., assignor to Cartier, Inc.,
New York, N.Y., a corporation of New York

Application November 29, 1957, Serial No. 48,709

Term of patent 7 years

(Cl. D29—23)

I claim:

The ornamental design for a trophy cup or the like, as shown.
